UNITED STATES PATENT OFFICE.

ARTHUR FORBES SCOTT, OF BRADFORD, ENGLAND.

INTERNAL-COMBUSTION ENGINE.

968,200.

Specification of Letters Patent. Patented Aug. 23, 1910.

Application filed December 30, 1905. Serial No. 294,031.

To all whom it may concern.

Be it known that I, ARTHUR FORBES SCOTT, M. I. Mech. E., a subject of the King of England, residing at 171 Swan Arcade, Bradford, England, have invented certain new and useful Improvements in Internal-Combustion Engines, of which the following is a specification.

This invention relates chiefly to improvements in "two stroke cycle" internal combustion engines in which the exhaust is controlled by the piston, and its main object is to provide an engine working with gas or an explosive mixture so that a scavenging charge of air is admitted before the explosive charge enters.

The accompanying drawing is a section of one cylinder of a vertical engine and its parts constructed in accordance with my improvements.

The motor cylinder A has an extension C below of larger diameter and is fitted with a piston of two diameters D and B, the part of larger diameter B having its underside 25 preferably open to the crank chamber M and acting as a pump, while the upper trunk part D is the motor piston. The lower part of the motor cylinder A is provided with exhaust ports E and ports O which are preferably, as shown in the drawing, on the opposite side and which are connected with the crank chamber M or bottom of the cylinder C by means of a separating pipe or passage T, which preferably has a spiral course as 30 shown so as to obtain a desirable length of passage with compactness. The motor and pump cylinders A and C contain respectively air and gas mixture inlet ports K and L and the motor piston D is provided with a deflector D^o on the top and has a recess J in 35 its side, and the whole is arranged so that when the piston which is connected to the balanced crank N approaches the top of the stroke the recessed port J therein connects 40 (as shown in the drawing) the air inlet K with the port O leading into the top of the separating passage T, and at the same time the pump part B of the piston uncovers the gas inlet L to the crank chamber M, and the 45 partial vacuum in the latter causes the scavenging and explosive charges to simultaneously enter the separating passage T and crank chamber M respectively, the proportions 50 of the two charges being dependent on 55 the size or opening of the two inlets or admitting ports K (or O) and L. The scav-

enging air is thus held in the separating passage T, and when the piston approaches the bottom of the stroke and has opened the exhaust E the air enters the cylinder by the 60 ports O and is followed by the gas mixture, when compression and ignition take place in the usual manner.

On account of the pre-admission of air to the cylinder a small rich explosive charge 65 may be used and the admission of same being delayed this distribution tends to prevent any loss at the exhaust ports, and also to avert danger of explosion in the crank chamber when the piston uncovers the ports 70 O, owing to the interposing column of air in the long passage T. The scavenging air besides having a cooling effect tends to raise the mean pressure in the cylinder and to enable the engine to run with greater range 75 of load, and so frees it from the chief disadvantages of the ordinary non-scavenging "two stroke cycle" engine, in which the volume of burned gases before ignition sometimes exceeds the volume of gas mixture 80 which has been admitted.

By suitably proportioning the gas and air inlets or admitting ports and the amount of opening of same; the dimensions of piston; and other parts; the required amounts of 85 gaseous and scavenging charges are obtained and the lengthened course of the separating passage prevents much admixture of the two charges.

The engine may be regulated by governing either of the passages, the separating passage being made large enough to hold the scavenging charge. Throttling the gas mixture at L will increase the amount of air entering at K—unless K is also throttled—and vice versa.

I claim:

A valveless internal combustion engine comprising a motor cylinder and a pump cylinder of different diameters, the latter 100 being of greater capacity than the former, a piston of two diameters, the smaller part working in the motor cylinder and the larger part in the pump cylinder, a crank chamber connected to the pump cylinder, a long separating passage of sufficient capacity 105 for retaining the whole of the scavenging charge of air and leading from the motor cylinder to the crank chamber, an air inlet port leading from the atmosphere directly through the motor cylinder, exhaust and gas inlet ports, a recess or port in the 110

motor part of the piston, which recess, at the top of the stroke, runs over and connects the air inlet port and the motor cylinder admission port which leads into one end 5 of the separating passage, while at the same time the pump part of the piston connects the said crank chamber with the gas inlet port by rising above the latter, the air entering the separating passage only, while 10 the gas enters the crank chamber, so that

when the charge of air in the separating passage enters the cylinder it precedes the gas charge from the crank chamber.

In witness whereof I have hereunto set my hand in presence of two witnesses.

ARTHUR FORBES SCOTT.
